STARTING AND OPERATING CIRCUITS AND
DEVICES FOR ELECTRIC DISCHARGE DE-
VICESPhilippe Waguet, Paris, France, assignor to Gen-
eral Electric Company, a corporation of New
YorkApplication June 16, 1948, Serial No. 33,387
In France June 14, 1947

4 Claims. (Cl. 315—165)

1

This invention relates to electric discharge devices of the type employing ionizable mediums such as gases or vapors, and more particularly to starting and operating devices and circuits therefor.

An object of my invention is to provide a new and improved starting and operating circuit for electric discharge devices energized from a direct current source.

Another object of my invention is to provide an improved and simplified operating circuit for luminous electric discharge devices or fluorescent lamps energized in series from a direct current source, and utilizing an auxiliary dependent alternating voltage source for heating the electrodes and starting the discharge in the lamps by means of an impulse induced therein.

My invention is of general applicability whenever it is desired to operate fluorescent lamps from a direct current supply. It has been found particularly useful in the illumination of cars on electrical railways and permits the immediate utilization of the direct current supplied to the locomotive, for instance the traction supply at 750 or 1500 volts, on the lighting circuits.

A feature of my invention is the utilization of an auxiliary direct-to-alternating current converter for heating the filamentary electrodes in the lamp and also for starting the discharge. This is achieved by means of a time-delay relay which permits the utilization of a voltage induced in the armature of the converter, upon the rupture of its field winding circuit, as a starting impulse for the lamps. This induced voltage is communicated to starting electrodes on the lamps by means of the primary circuit of a transformer whose secondary circuit provides heating current to the lamp electrodes.

For a more complete discussion of various circuits which may be utilized in operating fluorescent lamps from a direct current supply, reference is made to my copending U. S. application No. 28,223, filed May 20, 1948. Other applications and improvements in such circuits are disclosed in my copending U. S. applications Nos. 28,224, 28,225, and 28,226, filed May 20, 1948, and 33,385 and 33,386, filed June 16, 1948. The present invention is actually an improvement in the circuit disclosed in application No. 33,386. All of the above applications are assigned to the same assignee as the present invention.

For a better understanding of my invention, reference may be had to the following description taken in connection with the accompanying drawing and its scope will be pointed out in the appended claims. The drawing is a diagrammatic view of a plurality of electric discharge de-

2

vices connected in series and a starting and operating device and circuit therefor incorporating my invention.

Referring to the drawing, I have there illustrated one embodiment of my invention as applied to a group of two or more serially connected electric discharge devices wherein the notations for device 1a and the elements associated with device 1a are extended by indices to the other serially connected device or devices. The electric discharge device 1a (and 1b), such as a fluorescent lamp, therein illustrated compromises an elongated tubular or cylindrical envelope 2a having sealed into the ends thereof thermionic filamentary electrodes 3a and 4a. Filamentary electrodes 3a and 4a may comprise a coil, preferably in the form of a coiled coil of tungsten wire activated with oxides of alkaline earth metals such as a mixture of barium and strontium oxides. The envelope 2a contains a gaseous atmosphere such as a rare gas like neon, argon or mixtures thereof at a pressure of a few millimeters and a small quantity of mercury which, during the operation of the lamp, has a low pressure of the order of 10 microns. The device 1a may be a low pressure positive column lamp of a fluorescent type provided with a suitable phosphor or fluorescent coating. This fluorescent coating, upon excitation by the radiation produced by an electric discharge between the electrodes, transforms a shorter wave radiation due to the discharge into longer wave radiation such as radiation within the visible range. A pair of metal cups 5a and 6a serve to intercept the particles of emissive material sputtered from electrodes 3a and 4a, respectively. These cups are usually tied by means of connections, either outside or inside of the lamp, to the extremities 3a and 4a. A number of advantages result from the connections between filamentary electrodes 3a and 4a and the corresponding cups 5a and 6a, namely, utilization of cup 6a as an anode and eliminating the disintegration by ionic bombardment of filamentary electrode 4a, utilization of lamps that are usually employed with alternating current, reduction of operating voltage, doubling the life of the lamp by using successively the two filamentary electrodes, i. e., by turning the lamps around when one of the filaments becomes inoperative.

Serially connected devices 1a and 1b are connected across a suitable direct current power supply 7, 7' which, for example, may be a traction voltage of either 750 or 1500 volts, and in series with an auxiliary or second direct current source of supply 8 which, for example, may be a storage battery having a potential of 72

volts and connected in series with the devices 1a and 1b in such a manner that it will be charged by the current passing through the devices. The direct current source of supply 7, 7' supplies current to devices 1a and 1b through stabilizing resistances 9a and 9b. Resistances 9a and 9b, for example, may be iron or tungsten wire enclosed in hydrogen. A starting and operating circuit 10, 10' is connected across the auxiliary direct current supply 8 and comprises in series relationship a field winding section 11 of a dynamoelectric machine or rotary converter 12, a manual make-and-break switch 13, and a switching means 14 comprising a normally closed contactor 15 and a normally open contactor 16. Auxiliary electrodes 17a and 17b, mounted adjacent devices 1a and 1b, are connected to a common point 18 intermediate field winding section 11 and contactors 15 and 16 through an armature winding section 19 of dynamoelectric machine 12. The time-delay relay or switching means 14 comprises a coil 20 connected across the terminals of the direct current source of supply 7, 7'. Switching means 14, in addition, comprises a normally closed contactor 21 and a normally open contactor 22 in series with each other and with switch 13, armature winding section 19 of the dynamoelectric machine 12, and contactors 15 and 16 across the auxiliary source of direct current supply 8. A time-delay relay or switching means 23 comprising a contactor 24 in series with the direct current source of supply 7, 7' and a coil 25 connected across the auxiliary source of direct current supply 8 energizes the starting and operating circuits for devices 1a and 1b upon closure of switch 13. Thus, contactors 15 and 16 are connected in series with the conductor which connects the positive terminal of the battery 8 to the point 18, which both the armature winding section 19 and the field winding section 11 of the dynamoelectric machine 12 have in common. Moreover, the contactors 21 and 22 are connected in series with the conductor which connects the negative terminal of battery 8 with the other terminal of the armature winding section 19 by means of the switch 13, the other terminal of the field winding section 11 being connected to a common point between switch 13 and contactor 21.

Transformers 26a and 26b comprising primary winding sections 27a and 27b and center-tapped secondary winding section 28a and 28b, respectively, are connected in parallel across an alternating current supply 29, 29' produced by the dynamoelectric machine 12. The secondary winding sections 28a and 28b serve to heat filamentary electrodes 4a and 4b and to continue to heat these electrodes as long as primary winding sections 27a and 27b are energized. The center-tap of the secondary winding section 28b is connected through the ballasting resistance 9a to the filamentary electrode 3a of device 1a and the center-tap of the secondary winding section 28a is connected through the auxiliary source of direct current supply 8 to the negative terminal 7 of the direct current supply.

The operation of the circuit illustrated in the drawing is as follows: In the rest position, as shown in the drawing, contactors 16 and 22 are open and contactors 15 and 21 are closed. Upon the closing of the igniting switch 13, the coil 24 of the supply relay 23 is energized, contactor 24 closes and applies the system voltage to coil 20 of relay or switching means 14 and to the series-connected lamps in the entirety. Contactor 16

closes and energizes field winding section 11, contactor 22 closes a few tenths of a second after the closing of contactor 16, and applies voltage to the armature winding section 19 of the inverter which now begins to operate. The cathode filamentary electrodes 4a and 4b are heated. After a few seconds contactor 21 opens, interrupts the circuit of armature winding section 19 and discontinues the heating of the cathode filamentary electrodes; a few tenths of a second after the opening of contactor 21 contactor 15 opens and breaks the field winding section circuit 11, thus causing at point 18 a voltage impulse which is imparted, through the armature winding section 19, to the auxiliary electrodes 17a, 17b, etc. by way of the primary heating circuit to which these auxiliary electrodes are connected. This voltage impulse is similar to the voltage produced by induction in electrical motors and generators whenever a field winding circuit carrying a steady current is ruptured, as is well known in the art. Under the effect of that impulse the discharge lamps 1a, 1b, etc. ignite. If the system voltage should fail, relay or switching means 14 would immediately return to the rest position, contactors 15 and 21 would close, contactors 16 and 22 would open, and the armature and field circuits of the inverter would be open. When the normal system voltage is reestablished, switching means 14 functions as described above and the lamps in their entirety are thus re-ignited. Switching means 14 is so adjusted that it will return to the rest position only when the system voltage is slightly above the voltage at which the series connected lamps no longer will operate. If the system voltage drops below that value, switching means 14 will return immediately to the rest position, just as in the case of no voltage.

It is evident that the device which has just been described for a group of series-connected lamps can also be applied to any number of these groups connected in parallel.

The delayed operation of the contactors 15, 16, 21 and 22 of switching means 14 may be brought about, for example, by means of a mechanism actuated by coil 20 that causes the tilting of two glass bulbs containing mercury, the flow of which, suitably retarded by a capillary tube, serves to make or break the contacts. Other means for carrying out the switching function, such as mechanical timing devices for instance, will occur to those skilled in the art.

While a certain specific embodiment has been shown and described, it will, of course, be understood that various modifications may be made without departing from the invention. Thus, whereas a pair of lamps connected in series has been shown, it will be obvious that a single lamp or, again, a plurality of lamps may be utilized. Likewise, the auxiliary battery, which has been shown in the drawing, may be replaced by another source of voltage or eliminated entirely and the rotary converter energized from the principal direct current source. The appended claims are, therefore, intended to cover any such changes and modifications as fall within the true spirit and scope of the invention.

What I claim as new and desire to secure by Letters Patent of the United States is:

1. Apparatus for operating a gaseous luminous electric discharge device, of the type including a main thermionic electrode and a cooperating main electrode, comprising: said device, a unidirectional voltage source, and a ballast resistance; a rotary converter having a direct current

field winding, a direct current input circuit, and an alternating current output circuit; a transformer having a primary winding connected to said output circuit and a secondary winding connected to said thermionic electrode; a main discharge circuit constituted by connecting said device, in series with said ballast resistance, across said source; a time delay relay having two sets of contacts respectively connecting said field winding and said input circuit across said source, said relay operating to energize in sequence, first said field winding and then said input circuit, and said relay then operating to de-energize in sequence, after a predetermined time interval, first said input circuit and then said field winding, and an auxiliary starting electrode on said device connected to one side of the primary winding of said transformer for receiving the voltage induced in said output circuit upon the de-energizing of said field winding.

2. Apparatus for operating a gaseous luminous electric discharge device, of the type including a main thermionic electrode and a cooperating main electrode, comprising: said device, a unidirectional voltage source, and a ballast resistance; a dynamoelectric machine for converting direct current to alternating current, said machine comprising a field winding and an armature having direct current input terminals and alternating current output terminals; a transformer having a primary winding connected to said output terminals and a secondary winding connected to said thermionic electrode; a main discharge circuit constituted by connecting said device, in series with said ballast resistance, across said source; a time delay relay having two sets of contacts respectively connecting said field winding and the input terminals of said armature across said source, said relay operating to energize in sequence, first said field winding and then said armature, and said relay then operating to de-energize in sequence, after a predetermined time interval sufficient to permit heating of said thermionic electrode, first said armature and then said field winding; and an auxiliary starting electrode, located intermediate the ends of said device, connected to one of said alternating current output terminals, said auxiliary electrode thereby receiving, as a starting impulse, the voltage induced in said armature upon the de-energizing of said field winding.

3. Apparatus for operating a plurality of discharge devices, of the type including a main filamentary thermionic electrode and a cooperating main electrode, comprising: said devices, a unidirectional voltage source, and a ballast resistance; a dynamoelectric machine for converting direct current to alternating current, said machine comprising a field winding and an armature having direct current input terminals and alternating current output terminals; a transformer having a primary winding connected to said output terminals and a plurality of secondary windings connected to said filamentary electrodes; a main discharge circuit constituted by connecting said devices in series, the secondary winding associated with one device being connected to the cooperating main electrode of another in sequence, and the remaining secondary winding and cooperating electrode being connected, in series with said ballast resistance, across said source; a time-delay relay having two sets of contacts respectively connecting said field winding and the input terminals of the said

armature across said source, said relay then operating to de-energize in sequence, first said field winding and then said armature and said relay then operating to de-energize in sequence, after a time interval sufficient to permit the heating of said filamentary electrodes, first said armature and then said field winding; and auxiliary electrodes, located intermediate the ends of said devices, connected to one of said alternating current output terminals, said auxiliary electrodes thereby receiving, as a starting impulse, the voltage induced in said armature upon the de-energizing of said field winding.

4. Apparatus for operating a plurality of discharge devices of the type including a main filamentary thermionic electrode and a cooperating main electrode, comprising: said devices, a unidirectional voltage source, and a ballast of resistance; a dynamoelectric machine for converting direct current to alternating current, said machine comprising a field winding and an armature having direct current input terminals and alternating current output terminals; a transformer having a primary winding connected to said output terminals, and a plurality of secondary windings connected to said filamentary electrodes; a main discharge circuit constituted by connecting said devices in series, the secondary winding associated with one device being connected to the cooperating main electrode of another in sequence, and the remaining secondary winding and cooperating electrode being connected, in series with said ballast resistance, across said source; a storage battery connected in series between said main discharge circuit and said source, the polarity connections of said battery being such as to permit charging of same by the discharge current through said devices; a time-delay relay having two sets of contacts respectively connecting said field winding and the input terminals of said armature across said battery, said relay operating to energize, in sequence, first said field winding and then said armature, and said relay then operating to de-energize in sequence, after a time interval sufficient to permit heating of said filamentary electrodes, first said armature and then said field winding; and auxiliary starting electrodes, located intermediate the ends of said devices, connected to one of said alternating current output terminals, said auxiliary electrodes thereby receiving, as a starting impulse, the voltage induced in said armature upon the de-energizing of said field winding.
